UNITED STATES PATENT OFFICE.

JOHN P. ONDERDONK, OF PHILADELPHIA, PENNSYLVANIA.

SATCHEL OR HAND-BAG.

SPECIFICATION forming part of Letters Patent No. 340,001, dated April 13, 1886.

Application filed January 15, 1886. Serial No. 188,646. (No model.)

To all whom it may concern:

Be it known that I, JOHN P. ONDERDONK, of the city and county of Philadelphia, and State of Pennsylvania, have invented an Improvement in Satchels, &c., of which the following is a specification.

My invention has reference to the manufacture of satchels, hand-bags, and kindred articles; and it consists in certain improvements 10 fully set forth in the following specification and shown in the accompanying drawings, which form part thereof.

Satchels, hand-bags, &c., as heretofore constructed, be they formed of a number of pieces 15 of leather, canvas, or any other material, have generally been made with a large number of seams, either sewed or cemented, and in their construction the bodies are invariably turned inside out before sewing, and after sewing 20 turned back again, exposing the face of the material. This operation is slow and tedious, is expensive, and the structural condition of the finished article is more or less weak. In addition thereto, the lining is invariably made 25 separate and afterward placed within the bag so formed.

The object of my invention is, essentially, to cheapen the construction of bags by reducing the labor incident to their manufacture; 30 also to improve their appearance, and at the same time increase their durability.

In carrying my invention into practice I form the material of which the bag is to be composed into a tube, which may have bellows folds at its bottom, which bellows folds, 35 if continued to the upper end, are preferably wider at that end than at the other. The bottom of the tube may be closed in the act of making it by suitably folding the material; 40 but if left open in making the tube the free edges of the bottom end are secured together by sewing, riveting, or stitching, and the other or top end is secured to the ordinary hinged metallic bag-frame, the upper or free edge of 45 the bag-ends or bellows folds being united with the vertical portions of the frame. The bottom may now be pressed upward, so as to 50 form a flat, square, or rectangular face, and may then be retained in position by rivets or suitable sewing, and the satchel is complete. The lining is laid upon the material of which

the satchel is composed before being folded, and the act of forming the satchel-body proper simultaneously shapes the lining also. This construction reduces the labor to a minimum, 55 as it eliminates all unnecessary seams and obviates any necessity of turning the satchel-body inside out before sewing.

It is evident that while I prefer to use a single piece of material in the formation of the body 60 it may be formed of two or more pieces and yet be within my invention, which relates more particularly to the manner of forming the bottom.

In the drawings, Figure 1 is a perspective 65 view of a satchel embodying my invention and turned in such a position that the bottom is exhibited and the side folds pressed outward. Fig. 2 is a perspective view of the same, looking from above, and in which the 70 sides are pressed inward, forming bellows folds. Fig. 3 is a sectional plan view of same on line *x* *x*. Fig. 4 is a similar view on line *y* *y*. Fig. 5 is a sectional elevation on line *z* *z*. Fig. 6 is a plan view of a sheet of material 75 from which the bag is made before being folded up. Fig. 7 is a plan view of same folded up and having its lower ends stitched. Fig. 8 is a plan view of another and perhaps more desirable shape of material from which to make 80 the bag body, but embodying the same general features. Fig. 9 is a view similar to Fig. 6, but in which the bellows folds or edges of the ends are parallel; and Fig. 10 is a perspective view of a modified form of bottom. 85

A represents the body of the bag, and is preferably formed of one piece of material, shaped either like that shown in Fig. 6, 8, or 9.

In the case of the sheet shown in Fig. 6 the free edges are brought together and united, as 90 at *B*, either by cement, riveting, or stitching. The tube thus formed may be creased to form the sides or faces *D* and the bellows folds or ends *C*, which bellows folds or ends are preferably wider at the top than at the bottom. 95 The tube is then in the shape indicated in Fig. 7, and the lower edge is stitched, cemented, riveted, or otherwise fastened, as at *e*. If desired, the bottom edge alone may be made with bellows folds. The bottom is then 100 pressed upward into the rectangular or square shape, as indicated in Figs. 1 to 5, forming

the bottom face, F, which is preferably riveted fast to the diamond folds P of the bottom by rivets Q, which may also act as feet upon which the bag rests; or, in place of rivets, the edges 5 f may be sewed or otherwise fastened. This bottom then becomes fixed, and the tube can never regain the shape shown in Fig. 7. If desired, a stiffening or base board, H, may be secured upon the inside of the bottom F 10 to stiffen it still more, or it may be placed upon the outside thereof, as desired. The upper edges of the bellows folds, if used and carried to the top, may be bent outward to form diamond folds J, and the free edges i of said 15 bellows folds or ends C and sides D are united to the frame I, either by sewing, rivets, or otherwise, in the usual manner; and while it is shown as attached to a rectangular frame it is self-evident that this frame may 20 be curved or otherwise shaped. The tube may be distended and in that position attached to the square frame, which is also in an open position, and in this case the bellows folds and diamond fold at the top of the ends be- 25 come of no particular use.

The object of making the bag-body or the bellows folds or ends C wider at the top than at the bottom is to insure a more graceful form of bag when the body is in the position shown in 30 Fig. 1 or 2; but it is evident that this bag-body or bellows fold may be parallel, as indicated in Fig. 9. The lining L is placed upon the sheet A, forming the body of the bag when it is in the shape shown in Fig. 6 or 8, and 35 is folded up with the said body material, and is simultaneously sewed or shaped in the act of shaping and forming a satchel-body, and as the seam e is preferably upon the outside no fitting or adjusting of the parts is required 40 and no reversing of the material is necessary. Of course, it is evident that in place of stitching the lower part of the tube, as at e, the said tube may be formed into the shape of bottom indicated, and the edges lapped and 45 stitched by hand or machine, riveted, or otherwise fastened through from the interior to the outside of the bag, the particular method of fastening being immaterial to my invention.

In the form of material shown in Fig. 8, 50 which is perhaps the most preferable, the fold M would take the place of the seam e, and in place of the ends or the bellows folds C being without seams their inner or middle part would be secured along the free edges N, 55 which seams may also unite the lining to the body of the bag. In this case there would be two end seams, B, in place of one side seam and one bottom seam, e, occurring in the construction hereinbefore described. These seams 60 would be on the ends, as indicated in dotted lines, Fig. 1.

With the shape of sheet shown in Fig. 8 the bottom would be devoid of seams. The bottom diamond folds P may be turned out and 65 fastened over the bottom on the outside or to the ends of the body. In case of the diamond

fold being bent up on the end of the bag, it may be fastened by stitches or rivets, and would appear as indicated in dotted lines in Fig. 1, and it might be secured upon the inner 70 or outer walls of the end. It is also evident that where it is difficult to obtain a large sheet of material, or where the form of cutting necessitates too much waste of expensive material, the upper and lower parts of Fig. 8 75 may be united by a seam or otherwise at M; or, in the construction shown in Fig. 6, more than one vertical seam B may be used, and, if desired, said seams may come at the corners. In all cases, however, the formation of the 80 bottom will be substantially the same. Therefore, while I prefer the construction shown, I do not limit myself to the details thereof, as they may be modified in various ways without departing from my invention. 85

Having now described my invention, what I claim as new, and desire to secure by Letters Patent, is—

1. In a satchel or hand-bag, the metallic hinged bag-frame extending only part way 90 down on the ends of the bag-body, in combination with the body formed of one piece of material, and in which the angles or edges are formed by bends and folds without seams, substantially as and for the purpose specified. 95

2. The method of forming a satchel or hand-bag body from a tube, consisting in securing or sealing one end of the tube and folding it up to form a square or rectangular closed bottom with diamond-folds, whereby all seams 100 or sewing may be completed before forming the bottom, substantially as and for the purpose specified.

3. A satchel or hand-bag having a hinged frame and a box-shaped body, the ends there- 105 of where attached to the frame being wider than the part next to the bottom, whereby when the bag-body is completed the lower portion thereof will be box-shaped, substan- tially as and for the purpose specified. 110

4. A satchel or hand-bag having a hinged frame and a box-shaped body, the ends there- 115 of where attached to the frame being wider than the parts next to the bottom, and also a bottom made square or rectangular, but formed of the same and integral material forming the sides and ends, whereby seams around the lower edge or bottom of the bag are obviated, substantially as and for the purpose specified.

5. The method of forming a satchel or hand- 120 bag body from a tube of material having one end closed or sealed, consisting in opening said tube and pressing up a square or rectangular bottom and forming diamond folds, substantially as and for the purpose specified. 125

6. In a satchel or hand-bag, the frame J, in combination with the body A, having ends C provided with central seams, B, and made wider at the top than at the bottom, and bottom F, having diamond folds P, substantially 130 as and for the purpose specified.

7. In a satchel or hand-bag, the frame J, in

combination with the body A, having the ends C, and the bottom F, having the diamond folds P, substantially as and for the purpose specified.

5 8. In a satchel or hand bag, the frame J, in combination with the body A, having the ends C, and bottom F, having the diamond folds P, and rivets or feet G, securing the edges of the bottom F to the diamond folds P, substantially 10 as and for the purpose specified.

9. In a satchel or hand-bag, the frame J, in combination with the body A, having ends C, made wider at the top than at the bottom, and bottom F, having diamond folds P, substantially 15 as and for the purpose specified.

10. The method of forming a satchel or hand-bag body from a tube of material having one end closed or sealed, consisting in opening said tube and pressing up a square or rectangular bottom and forming diamond folds, and said diamond folds being united to the body by sewing or riveting, to make said bottom rigid, substantially as and for the purpose specified.

25 11. A satchel or hand-bag consisting of the

frame J, in combination with the body A, made of the single piece of material forming the sides D and ends C, the latter being provided with central or middle seams, B, substantially as and for the purpose specified.

12. A satchel or hand-bag consisting of the frame J, in combination with the body A, made of the single piece of material forming the sides D and ends C, the latter being provided with central or middle seams, B, and 30 made wider at the top than at the bottom, substantially as and for the purpose specified.

13. In a satchel or hand-bag, the body portion formed with a square or rectangular bottom, the ends of said bottom being formed 40 with diamond folds, and said diamond folds being bent up or over and secured to one of the faces of the bag, substantially as and for the purpose specified.

In testimony of which invention I hereunto 45 set my hand.
